Mellinger; Samuel Mellinger**

Emmanuel Meily Jr. John Hollinger and Emanuel Hollinger
The inventors referred to in this Letter Patent and making part of
the same, containing a description in the words of the said Emmanuel
Meily Jr. John Hollinger and Emanuel Hollinger themselves
of their Improvement in the Scorn or Machine for Drawing Crews
hing, carpets, Draper, and other kinds of fancy work.

To all whom it may concern, Be it known that we Emmanuel
Meily Jr. John Hollinger and Emanuel Hollinger of the Borough
of Gibsonon in the County of Gibson, and the state of Penn-
sylvania, have invented certain improvements in the Scorn or
machine for drawing carpets, carpets, Draper, and other kinds
of fancy work and we do hereby declare that the following is a full and
exact description thereof, reference being had to the drawings which
accompany and make part of this Specification. We may
remark that this machine resembles that in common use, but by
means of the improvements which we have made, we pro-
cure, and serve the same purpose with less in the old plan, an
consequence of which but one half of the machine formerly used and
as required by us. A. L. A. Fig. 1 is the ordinary form of the base
3. C. D. E. are blocks, when the foot is placed upon the blocks
B. and it is forced down, a wire or cord leading from it and
connects with the lever G. draws one end of it down, and re-
sists the other which is attached to the figure holding one of
consecutives them, at the same time that this is raised,
one half of the binder is raised also, the cord being attached to
the lever, which works the binder as shown in the drawings.
The next binder operates in a similar manner upon the other
half of the binder. The dotted lines at G represent the cords by
which the attachment to the figure binder is formed, and
also the end of the sliding piece which catches the hook in rais-
ing the figure holdly. The projecting iron rod H. having a
rotation wheel at its end, is attached to the sliding piece, and

of course uses within it. In so doing, this friction roller is brought into contact with the curved spring piece *b*, the lower end of which is attached to what we call the swinging frame *J*. These parts are all double, that is they are repeated at the opposite end, and of course are not seen in the drawing. The needle beam *K* is turned in the swinging frame *J* upon the swinging frame *J* in a case *M*, which enables upon going upon the wheel *M*, there being four such pieces, at equal distances apart, the case *M* is shown in the drawing ^{one} ~~one~~ ^{case} upon ^{one} of them, and the needle beam *K* is in operation with the pattern card *L*. When the swinging frame *J* is turned forward the case *M* catches upon the next piece, not seen in the drawing, being ^{turned} ~~one~~ ^{one} in the middle by the swinging frame *J*, the needle beam *K* is ^{turned} ~~one~~ ^{one} ~~one~~ ^{one} forward of the way round at every other forward swing of the swinging frame. Behind the wheel *M*, and on the same shaft with it there is ^{Fig. 2. M.} ~~Fig. 2. M.~~ ^{being the round, and Fig. 3. the oval wheel.} what we denominate the oval wheel. These two wheels are shown. The hooks *O* & *P*, the round and oval wheels are solely intended to operate upon the needle beam. The situation in which the hook *O* & *P* stand in the drawing results from their being separated by the contact of the longest diameter of the oval wheel. When the swinging frame moves forward being set ^{into operation} ~~into motion~~ by one of the figure needles, the needle beam and pattern card on it, remain in the same situation, in the return of the swinging frame, the contact of one of the pins on the round wheel *M*, before mentioned, and from both wheels give forth round and consequently the figure hook *O*, passing on the shortest diameter of the oval wheel, and at ^{Fig. 3.} ~~Fig. 2.~~ ^{it turns to} ~~it turns to~~ takes hold of the needle beam, at the second ^{rotation} ~~rotation~~ swinging forward of the swinging frame. Being set ^{into operation} ~~into motion~~ by the other figure needle, the needle beam being held by the hook *O*, course turns round in forth and passes a new pattern card toward the needle. A card *Q* connects the outer ends of the two hooks *O* & *P*. The weight *R*, has a cord attached to its central part over a pulley *S* to the right in front of the machine and is connected with the hooks *O* & *P* as seen in the drawing. When

When the workman has proceeded, with his work to the extent of this pattern, whilst the weight (R) is hanging upon a pin, being inactive, and wishes to weave the rest of his pattern in the reverse order, all he has to do is take the weight $\frac{3}{4}$ off of the pin: let it gradually take hold of the end which will then swing the two books (A & B) up and now whereas the upper book (C) did before spiral upon the needle beam, now the lower book takes hold of the needle beam and throws it one fourth round in the reversed order and also presents the pattern - cards towards the needles in the reversed order.

We carry the pattern cards out by spanning them over friction rollers as shown at 24. If we also place a tool roller

26, in the doubling of the pattern cards which keeps them in a proper state of tension, and causes to work with regularity. In our first specification we omitted to describe an improvement made adopted, and then used by us, of preparing the pattern cards.

The usual method of doing this is to place the prep. board of which the cards are made, between two pieces of metal similarly perforated, and to punch them with solid round punches. Instead of this we take a single plate preferably of metal, and confine it upon a block of wood, resting upon the end grain thereof. we then cut the prep. board, placed between the plate, and the wood, by means of a hollow punch. This punch has a wire passing through its hollow, a barrel coiled into a spiral spring so as to push out the pieces as they are cut. This arrangement is shown at Fig. 3. and needs no further description. This machinery may however be modified and arranged, whilst the same general principles, or modes of action as those upon which our improvement are dependent, may be substantially retained, in claimimg certain thoughts our invention. therefore it is to be understood that we do not intend to limit ourselves to the precise modes and forms by us set forth, but to vary the same, in any way we may deem proper. whilst the same results are attained by analogous means.

meets. We claim as our invention the general arrangement of the parts connected with the round and oval wheels, as herein described, for the purpose of operating upon the needle shaft, in the manner, and for the purpose set forth. We claim the manner of carrying out the pattern cards, by means of friction rollers, and, the steadyng the same by means of a loose roller on the doubling stand. We claim also the mode described of preparing the pattern cards upon a block of wood, by means of a hollow punch and cleaver operated upon by a spring.
